UNITED STATES PATENT OFFICE.

MOSES B. SHANTZ, OF ROCHESTER, NEW YORK.

DESIGN FOR A BUTTON.

SPECIFICATION forming part of Design No. 34,367, dated April 16, 1901.

Application filed March 13, 1901. Serial No. 61,029. Term of patent 7 years.

To all whom it may concern:

Be it known that I, MOSES B. SHANTZ, a citizen of the United States, and a resident of Rochester, in the county of Monroe and State 5 of New York, have invented and produced a new and original Design for a Button, of which the following is a full, clear, and exact description.

Reference is to be had to the accompanying 10 drawings, forming a part of this specification, in which similar characters of reference indicate corresponding parts in both the figures.

Figure 1 is a front face view of a button, showing my design; and Fig. 2 is a sectional 15 side elevation of the same on the line 2 2 in Fig. 1.

The obverse of the button consists of a spherical center A, appearing with connected apertures A' and surrounded by a circular

rim B, arched in cross-section to form at its 20 inner edge with said center A a circular joint C, the outer portion of said rim being rounded off to the reverse of the button, said reverse appearing convex at the middle portion D and having a gently annular dish E to the 25 rounded edge of the rim.

Having thus fully described my invention, I claim as new and desire to secure by Letters Patent—

The design for a button herein shown and 30 described.

In testimony whereof I have signed my name to this specification in the presence of two subscribing witnesses.

MOSES B. SHANTZ.

Witnesses:

A. VANDERKORDE,
E. S. FLOOD.
